(57) **CLAIM**

The ornamental design for a portable information terminal, as shown and described.

DESCRIPTION

FIG. 1 is a perspective view a portable information terminal showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and

FIG. 7 is a bottom plan view thereof.

FIG. 8 is a reference perspective view thereof in the closed position;

FIG. 9 is a reference front elevational view thereof in the closed position;

FIG. 10 is a reference rear elevational view thereof in the closed position;

FIG. 11 is a reference left side elevational view thereof in the closed position;

FIG. 12 is a reference right side elevational view thereof in the closed position;

FIG. 13 is a reference top plan view thereof in the closed position; and,

FIG. 14 is a reference bottom plan view thereof in the closed position.

The portions shown in broken lines in the figures are for illustrative purposes only and form no part of the claimed design.
